UNITED STATES PATENT OFFICE.

NICOLA LAROCCA, OF NEWARK, NEW JERSEY.

VALVE FOR FLUSHING TOILET-BOWLS.

1,145,249.

Specification of Letters Patent.

Patented July 6, 1915.

Application filed October 14, 1914. Serial No. 868,627.

To all whom it may concern:

Be it known that I, NICOLA LAROCCA, a subject of the Kingdom of Italy, residing at No. 136 Bank street, in the city of Newark, county of Essex, State of New Jersey, have invented a new and useful Improvement in Valves for Flushing Toilet-Bowls, of which the following is a specification.

My invention relates to valves for flushing toilet bowls and has for its object to provide an easily operable valve for this purpose illustrated in the accompanying drawing, in which—

Figure 1 shows, in vertical section, my improved valve in connection with the usual flushing tank and bowl. Fig. 2 is an enlarged vertical sectional view of my valve.

Referring in detail to the drawing, 1 is the supply pipe branched from the house water supply and adapted to fill the conventional flushing tank 2 which delivers through pipe 3. At a conveniently operable position along pipe 3 my improved valve is mounted. It consists of a cylindrical casing 4 having an inlet 8 piercing the upper wall, an outlet 9 in axial alinement with inlet 8 and a passage 10 on the side near the base, each of the passages 8, 9, and 10 being threaded; 8 and 9 for the reception of pipe 3 and the continuation thereof respectively, while passage 10 receives the threaded arm of an L-shaped end 5 of a pipe 7 which connects member 4 with the bowl. The threaded arm of the L-shaped member 5 extends within the casing 4 and is formed to provide a slanting seat for a flap valve 11, which is pivotally mounted as at 12 and

adapted to make a water-tight contact with the seat. A gasket 13 insures watertight connection between said arm and casing 4. 40 The valve member 11 is operated by means of a handle 6 and lever 14 both mounted upon squared portions of a suitable shaft 15. In normal positions the inner end of lever 14 contacts with about the central portion 45 of the inner surface of member 11 and on pulling the handle 6 toward the operator the upper face of lever 14 will open the valve member 11, thus allowing water to flow from the flushing tank into the bowl. 50

Various changes might be made in the general form and arrangement of the parts described without departing from the spirit of my invention.

I claim:

The combination of a chamber 4 having an inlet in its top and an outlet leading from its bottom, of a tubular outlet leading through one side near the bottom of the chamber, the inner end of the tubular outlet slanting downward to the adjacent edge of the first-named outlet and carrying a flap valve hinged to its upper edge, the outer end of the tube bending downward, an operating shaft mounted transversely in the angular portion of the tube, and a valve-operating arm on the shaft having its end in engagement with the inner surface of the valve.

NICOLA LAROCCA.
